US00D766160S

(12) **United States Design Patent** (10) Patent No.: **US D766,160 S**
(45) Date of Patent: ** Sep. 13, 2016

(54) **CAR MODULE**

- (71) Applicant: **Automotive Data Solutions Inc.**,
Montreal (CA)
- (72) Inventors: **Franco Barassi**, Montreal (CA);
Sébastien Boulais, McMasterville (CA)
- (73) Assignee: **Automotive Data Solutions Inc.**,
Montreal, Quebec (CA)
- (**) Term: **15 Years**
- (21) Appl. No.: **29/533,385**
- (22) Filed: **Jul. 16, 2015**

Related U.S. Application Data

- (62) Division of application No. 29/455,506, filed on May 21, 2013, now Pat. No. Des. 737,194.

(30) **Foreign Application Priority Data**

- Nov. 21, 2012 (CA) 148614
- (51) **LOC (10) Cl.** **12-16**
- (52) **U.S. Cl.**
USPC **D12/400**
- (58) **Field of Classification Search**
USPC D12/400, 190, 196, 93, 91, 173, 183,
D12/88, 92; D14/258
CPC H01R 2201/26; B60R 16/0207
